Primary Examiner—Antoine Duval Davis

[57] CLAIM

The ornamental design for a thermostat housing with compound curved surfaces, as shown and described.

DESCRIPTION

FIG. 1 is an elevation view of the front of the housing, the rear elevation view being plain and unadorned; FIG. 2 is an elevation view of the right side of the housing viewed from the front;

FIG. 3 is an elevation view of the top of the housing the bottom view being a mirror image; and,

FIG. 4 is a perspective view of the housing as viewed from above and to the left.

The thermostat housing with compound curved surfaces is shown in a condition of use in FIGS. 1-4.
